RAZOR GUARD

Albert Winterkorn, Columbus, Ohio

Application April 23, 1935, Serial No. 17,816

7 Claims. (Cl. 30—79)

This invention relates to guard attachments for razors and among the objects of the invention are: to provide a guard for the blades of standard razors by which the protecting edges of the guard may be adjusted to assume desired related positions to the cutting edge of the razor blade and to permit this relationship to be maintained throughout the life of the razor blade, despite variations in the form of its cutting edge due to the effects of honing, stropping and wear; the provision of a guard which is forced by positive spring pressure toward the back edge of the razor blade and wherein adjusting screws are provided in connection with the guard to counteract the spring pressure to maintain the desired counter-relation between the protecting edges of the guard and the cutting edge of the razor blade; in the provision of a razor guard which will be simple to apply and adjust with respect to the associated razor blade, and moreover, one which may be conveniently removed to avoid interference with the normal washing or stropping of the associated blade.

For a further understanding of the invention, reference is to be had to the following description and the accompanying drawing, wherein:

Fig. 1 is a perspective view of a standard type of razor provided with the guard comprising the present invention;

Fig. 2 is a view in side elevation of the guard operatively mounted on the blade of a razor;

Fig. 3 is a transverse vertical sectional view on the line III—III of Fig. 2;

Fig. 4 is a similar view on the plane indicated by the line IV—IV of Fig. 2;

Fig. 5 is a horizontal and longitudinal sectional view on the line V—V of Fig. 2;

Fig. 6 is a view in side elevation of a slightly modified form of my invention;

Fig. 7 is a vertical transverse sectional view on the line VII—VII of Fig. 6.

Referring more particularly to the drawing, the numeral 1 designates the blade of a standard type straight edge razor, the blade being provided with the usual handle extension 2 which is pivotally connected as at 3 with a handle 4, and it is to a razor of this type that the guard 5, comprising the present invention, is adapted to be applied as a safety appliance to protect the face during shaving operations.

The guard comprises a metallic casing in which the blade 1 is received, and in this instance the casing includes side walls 6 and 7 arranged adjacent to the sides of the blade 1, the wall 7 terminating at its upper edge in a horizontal top wall

8 with which are formed hinges 9, providing for relative separation between the walls 6 and 7 to facilitate removal of the casing from the razor blade. The lower edges 10 of the walls 6 and 7 are provided with thickened guard ribs 11 which are adapted to be so correlated with the cutting edge 12 of the blade 1 as to prevent the latter from cutting the face during shaving, the ribs 11 being substantially fully coextensive with the length of the edge 12.

To prevent undue separation of the walls 6 and 7 and to lock the same in holding engagement with the sides of the blade 1, the wall 7 has pivotally connected with one end thereof a latch 13, the latter being provided with a horizontal edge 14 arranged to overlie the top wall 8. The edge 14, in turn, is formed with a depending resilient lip 15 disposed for engagement with the inclined outer surface of a bearing pad 16, formed in connection with the medial portion of the wall 6. When the latch 13 occupies the position disclosed in Figs. 1, 2 and 3, the resilient lip 15 frictionally presses upon the inclined outer surface of the pad 16 and thereby holds the walls 6 and 7 in firm engagement with the sides of the razor blade. By lifting the latch 13 and rocking the same about its pivotal connection 17 with the wall 7, the lip 15 may be raised so as to clear the wall 6, thereby permitting of the ready separation of the walls 6 and 7 through the hinge connections 9.

To hold the guard ribs 11 in proper protecting relationship with the cutting edge 12 of the blade 1, the back of said blade, contiguous to the handle extension 2, is provided with a frictionally mounted clamp 18, from which projects in a forward direction a pair of resilient arms 19. These arms have their outer ends terminated in ball shaped extremities 20 which are normally received within sockets 21 provided in connection with the upper leg 14 of the latch 13. The construction and positioning of the arms 19 are such as to cause them to exert a downward force on the guard as an entirety so that the ribs 11 will be advanced toward the cutting edge 12. This action, however, is counteracted or limited by a pair of adjusting screws 22, the threaded shanks of these screws being carried by the top wall 8 of the guard casing and the lower ends of said shanks are adapted to engage with the back edge 23 of the blade 1. By reason of the independent adjustment afforded by the screws 22, the relationship between the ribs 11 and the cutting edge 12 may be regulated to obtain the desired safety conditions. Adjustment of the screws 22 will be necessitated from time to

time as the cutting edge of the blade 1 wears through the effects of use, honing and stropping.

In view of the foregoing, it will be seen that the present invention provides an easily applied and 5 readily adjustable safety guard for so-called "straight-edge" razors. The construction of the guard is such that it will not in any way interfere with the normal use of the razor in face shaving operations and when it is desired to clean, strop 10 or hone the razor, it is a simple matter to remove the guard from the blade. When the guard attachment is applied, the latch 13 and its associated lip 15 retain the hingedly connected sections 15 of the guard casing in clamping relationship with the blade 1. The resilient arms 19 force the guard in a downward direction on the blade so that a predetermined relationship will exist between the ribs 11 and the cutting edge 12, providing for normal use of the razor but preventing injury 20 to the face. Through the use of the screws 22, very fine adjustments in the relationship of the guard to the edge of the razor is obtainable and at the same time compensation is provided for the loss in shape of the cutting edge of the 25 razor due to conditions of wear and service.

The invention is of course susceptible to considerable variation in mechanical details without departing from the essential features of construction above described. For instance, as disclosed 30 in Fig. 6, the guard casing 24 is formed from a resilient metal with the side walls 6a and 7a thereof integrally united through the horizontal top wall 8a, the casing being devoided of the hinges provided in the form of the invention illustrated in Fig. 1 for permitting separation between the walls 6 and 7. Thus in Fig. 6, a guard casing is slipped over the back of the blade 1 from one end of said blade and the walls 6a and 7a resiliently separated. Also, in Fig. 6, the top 35 wall 8a is equipped with a detachable bracket 25, the latter terminating at its lower end in a lip 26, which receives the outer end of a spring 27 carried by a clamp 18a. In this form of my invention, the pressure exercised by the outer end 40 of the spring 27 forces the guard casing downwardly on the blade 1, in substantially the same manner as the arms 19. Also, in Fig. 6, the guard casing is provided with adjusting screws 22a for regulating the positions of the ribs 11a with the 45 cutting edge of the razor blade.

What is claimed is:

1. A razor guard comprising a casing formed to resiliently embrace the sides of a razor blade, the lower edges of said casing being formed with ribs 55 disposed in guarding relationship with the cutting edge of the razor blade, a clamp formed to be separately mounted on the back of the razor blade independently of the guard casing, a spring secured at one end to said clamp and having its 60 outer resilient end arranged to engage with the guard casing to force the ribs of the latter toward the cutting edge of the blade, and threaded means carried by said casing and engageable with the back of the razor blade for aligning said ribs in 65 guarding relationship with the cutting edge of the razor blade.

2. Safety appliances for hollow ground razor blades comprising a metallic casing formed to include resiliently separable side walls arranged 70 to be frictionally received upon the razor blade, said walls terminating in guarding ribs arranged to lie and extend contiguous to the cutting edge of the razor blade, spring means detachably carried by the razor blade separately from the guard casing and cooperative with the latter to force 75

said ribs toward the cutting edge of the blade, and threaded means arranged at each end of the guard casing cooperative with the back of the razor blade to limit the action of said spring means and maintain said ribs in parallel relationship with 5 the cutting edge of said blade.

3. Safety appliances for hollow ground straight edge razor blades comprising an inverted U-shaped casing including resiliently separable side walls, the ends of said casing being opened, said 10 side walls terminating at their lower ends in ribs arranged to extend parallel with and contiguous to the cutting edge of the razor blade, a clamp frictionally received on the back of the razor blade separately from said casing, spring means projecting from said clamp and cooperative with said casing to force the latter downwardly upon the razor blade, and adjusting screws arranged at each end of said casing and cooperative with the back of the razor blade for limiting the operation 15 of said spring means and regulating the spaced relationship existing between said ribs and the cutting edge of the blade.

4. Safety guard mechanism for straight edge razors comprising a casing composed of a pair 25 of hingedly connected sections between which a razor blade is adapted to be positioned, latch means for retaining said sections in clamping relationship with an associated blade, a spring support detachably carried by the back of the 30 razor blade separately from said casing, a spring projecting from said support, said spring having its free end arranged for engagement with said casing to force the latter downwardly upon said blade, and threaded means carried by said casing and cooperative with the back of the razor blade to control the relationship between the lower longitudinal edges of the casing sections 35 and the cutting edge of said blade.

5. Guard mechanism for straight edge razors 40 comprising a casing composed of hingedly connected sections between which the blade of a razor is adapted to be frictionally received, resilient latch means for retaining said sections in 45 embracing relationship with the sides of the razor blade, a spring detachably carried by the back of the razor blade separately from said guard casing, the free end of said spring being disposed for engagement with said casing to force the latter downwardly upon said blade, and threaded adjusting means disposed at the opposite ends of said casing and cooperative with the back of the razor blade in varying the relationship between the lower longitudinal edges 50 of said guard casing and the cutting edge of said blade.

6. Guard mechanism for a straight edge razor comprising a casing of inverted U-shaped cross section, the side walls of said casing being resiliently separable and the ends being open, a clamp separately secured to the back of said 60 razor adjacent the handle extension, a spring member secured at one end to said clamp and engaging said casing with the other end to force said casing toward the sharpened edge of said razor, and adjusting screws carried by the back of said casing and engaging the back of said razor to resist the force of said spring and vary the spacing of the lower edge of the side walls 65 of said casing from the sharpened edge of said razor.

7. Guard mechanism for a straight edge razor comprising an inverted U-shaped casing provided with an open end, the side walls of said 75

casing being resiliently separable, adjusting means carried by said casing for varying the spacing of the lower edges of the side walls from the sharpened edge of said razor, a clamp secured to said razor between the casing and the handle of the razor and a spring carried by said clamp

and engaging said casing to move the same toward the sharpened edge of said razor, said clamp and said casing being separately removable from said razor.

ALBERT WINTERKORN.
